UNITED STATES PATENT OFFICE.

MELANCTHON E. ZELLER, OF BLUFFTON, ASSIGNOR TO THE EBERHARD MANUFACTURING COMPANY, OF CLEVELAND, OHIO.

DESIGN FOR A TRACE-CARRIER.

SPECIFICATION forming part of Design No. 22,427, dated May 9, 1893.

Application filed March 8, 1893. Serial No. 465,180. Term of patent 14 years.

To all whom it may concern:

Be it known that I, MELANCTHON E. ZELLER, of Bluffton, in the county of Allen and State of Ohio, have invented a new and original Design for Trace-Carriers, of which the following is a full, clear, and exact description, reference being had to the accompanying drawings, forming part of this specification, in which—

Figures 1 and 2 are plan views of opposite sides of a trace carrier embodying my design; and Fig. 3 is a side elevation thereof.

The design consists in a trace carrier shaped substantially as shown in the drawings.

In the drawings, 2 represents the marginal frame of the trace-carrier, 3 is a loop project-

ing therefrom, and 4, 4, are curved bars opposite the loop. These bars extend upwardly from the marginal frame, and are thence curved downwardly, and at their ends have 20 portions 4', which project in the plane of the marginal frame as shown.

I claim—

The design for trace carriers substantially as herein shown and described.

In testimony whereof I have hereunto set my hand.

MELANCTHON E. ZELLER.
